COMBINATION SHADE AND CURTAIN SUPPORT

Robert C. Crates, Findlay, Ohio

Application June 16, 1936, Serial No. 85,601

2 Claims. (Cl. 248—256)

My invention relates to improvements in combination shade and curtain supports.

My invention is designed primarily to provide a combination unitary support of this character

5 embodying shade brackets and both curtain and over-drape brackets and extensible, as a unit, to vary the distance between the shade brackets, for different lengths of shade rollers, and the length of the curtain and over-drape brackets in fixed 10 relation to accommodate curtains and over-drapes of different widths, the shade brackets being independently adjustable to vary the distance between the shade brackets without altering the fixed relation of the other brackets and the length 15 of the curtain and over-drape brackets being variable without varying the distance between the shade brackets so that shades and curtains and over-drapes of different lengths may be hung on the support and variations in draping effects 20 being readily obtained with numerous widths of curtains and drapes.

Another object is to provide a unitary support of the character and for the purpose set forth equipped with means common to all the brackets 25 of securing the same to a window casing and constructed so that the curtain and over-drape brackets may be detached from the shade brackets so that the latter may be used alone, or, the over-drape bracket detached and the curtain and 30 shade brackets used together.

Other objects are to provide a combination support adapted for the purposes above set forth and for adjustment of the over-drape bracket to and from the curtain bracket.

35 Still another object is to provide a combination shade and curtain support having the characteristics above noted and in which all parts are strong, durable, readily assembled and disassembled and comparatively inexpensive to manufacture.

To the accomplishment of the above and other objects presently appearing a preferred embodiment of my invention has been illustrated in the drawing, and described in detail and defined in 45 the following description and claims, respectively.

In said drawing:

Figure 1 is a view in top plan of my improved combination shade and curtain support.

Figure 2 is a view in front elevation.

50 Figure 3 is a fragmentary view in horizontal section, of one end of said combination support.

Figure 4 is a view in transverse section taken on the line 4—4 of Figure 3 looking in the direction indicated by the arrows, and drawn to an enlarged scale, and

Figure 5 is a view in section taken on the line 5—5 of Figure 3 looking forwardly of said support.

Referring to the drawing by numeral, the illustrated embodiment of my invention comprises a pair of shade supporting brackets 1 each comprising an intermediate web part 2 designed to support the shade roller 3 in the usual manner, a right angled base flange 4 adapted to be attached as by screws 5 to the window casing, indicated at 6, and a right angled extension 7 projecting laterally from the web part 2 toward the outer side of the window casing.

An extensible curtain bracket 8 is mounted upon the shade brackets 1 as follows. The curtain bracket 8 comprises a pair of flat curtain supporting bars 9 connected together in aligned end to end relation by means of the usual form of sleeve-like coupling 10 slidably connecting the opposed ends of the bars 9 for adjustment of said bars endwise relative to each other. The opposite ends of the bars 9 are detachably connected to the shade brackets 1 by means of a pair of U-shaped coupling members 11 each comprising front and rear legs 12 and 13 the rear legs being slidably mounted upon the extensions 7 for adjustment parallel with the bars 9 and the front legs 12 slidably supporting the said opposite ends of the bars 9.

An extensible over-drape bracket 14 is mounted upon the coupling members 11 as follows. The over-drape bracket 14 comprises a pair of flat bars 15 connected together in end to end aligned relation by means of a sleeve-like coupling 15' similar to coupling 10 and in which the opposed ends of the bars 15 are slidably mounted so that said bracket is lengthwise extensible. The opposite ends 16 of the bars 14 are bent at right angles rearwardly and terminate in sleeve-like extremities 17. A pair of right angled bars 18 are mounted upon the rear legs 13 of the coupling members 11 for adjustment lengthwise of the bracket 8 and to provide forwardly extending arms 19 spaced from the ends of the coupling members 11 and slidably supporting the sleeve-like extremities 17 whereby the over-drape bracket is adjustable toward and from the curtain bracket 8. The bars 18 are preferably mounted upon the coupling members 11 by means of sleeve-like guide plates 20, secured to the coupling in any suitable manner and in which the bars 18 are mounted for sliding adjustment to fixed positions by means of slots 21 in said bars, respectively, and rivets 22 passing through the slots 21 and secured in said coupling members.

The shade brackets 1 may be formed of any

suitable light weight metal and the curtain bracket 8, over-drape bracket 14, and coupling members 11 of the usual thin light sheet metal rolled to form the sleeve-like ends on the legs 12 and 13 of the coupling members, the sleeve-like extremities 17 on the bars 15 and the coupling members 10 and 15'.

As will be clear the shade brackets 1 may be adjusted inwardly toward each other for supporting shade rollers of different lengths without altering the fixed relation of the curtain and over-drape brackets 9 and 14. By sliding the coupling members 11 on the curtain shade brackets 1 the curtain and over-drape brackets 9 and 14 may be extended or contracted in fixed relation as regards relative length and by adjusting the right angled bars 18 on the coupling members 11 and said coupling members on the curtain shade brackets 1 the curtain bracket 8 and over-drape bracket may be independently extended or contracted. By detaching the coupling members 11 from the shade brackets 1 both the curtain and drape brackets may be removed as a unit and by detaching the bars 15 from the bars 18 the over-drape bracket may be detached alone. As will be clear the over-drape bracket 14 may be adjusted toward and from the curtain bracket by sliding its extremities 17 back and forth upon the bars 18.

30 The foregoing is a detailed description of a preferred embodiment of my invention and it is believed that its construction and advantages will be clear therefrom.

It is to be understood, however, that the details described in the foregoing are illustrative rather than restrictive and that right is herein reserved to modifications of such details falling within the scope of the claims appended hereto.

5

What I claim is:

1. A combination shade and curtain support for attachment to a window casing comprising, a pair of shade supporting brackets adapted to be attached to said casing and having a lateral extension, respectively, an extensible curtain bracket having its opposite ends slidably mounted on said extensions, and a second extensible curtain bracket having its opposite ends slidably mounted on the ends of the first mentioned curtain bracket.

10

2. A combination shade and curtain support for attachment to a window casing comprising, a pair of shade supporting brackets adapted to be attached to said casing and having a lateral extension, respectively, and a pair of U-shaped coupling members slidably mounted on said lateral extensions, respectively, and slidably supporting the opposite ends of a curtain rod in advance of said shade brackets, and a pair of angled bars, a guide member carried by each coupling member for said angled bars to slidably support said angled bars, for adjustment lengthwise of said curtain support.
